(57) **CLAIM**

The ornamental design for a tablet computer as shown and described.

DESCRIPTION

Tablet computer

2.1 is a front view of a tablet computer, showing the new design;

2.2 is a back view thereof;

2.3 is a left view thereof;

2.4 is a right view thereof;

2.5 is a top view thereof;

2.6 is a bottom view thereof;

2.7 is a front perspective view thereof; and

2.8 is a back perspective view thereof.

The broken lines in the reproductions depict portions of the tablet computer that form no part of the claimed design.

1 Claim, 3 Drawing Sheets
